[57] CLAIM

The ornamental design for a combined fishing rod and reel with gun-shaped handle, as shown.

DESCRIPTION

FIG. 1 is a perspective view of a combined fishing rod and reel with gun-shaped handle illustrating my new design;

FIG. 2 is a right side elevational view thereof;

FIG. 3 is a left side elevational view thereof;

FIG. 4 is a top view thereof; and

FIG. 5 is an end view thereof.

FIG. 1

FIG. 5
